[57] CLAIM

The ornamental design for a compass clinometer, as shown and described.

DESCRIPTION

FIG. 1 is a top perspective view of a compass clinometer showing my new design;

FIG. 2 is a top plan view thereof;

FIG. 3 is a rear elevational view thereof;

FIG. 4 is a right side elevational view thereof;

FIG. 5 is a bottom plan view thereof;

FIG. 6 is a front elevational view thereof;

FIG. 7 is a left side elevational view thereof.

In FIGS. 1 and 2 typical compass clinometer indicia shown in broken lines is environmental only and forms no part of the claimed design.
